UNITED STATES PATENT OFFICE.

THOMAS F. GANNON, OF ROCHESTER, NEW YORK.

EXCAVATING AND FILLING APPARATUS.

1,142,692.

Specification of Letters Patent.

Patented June 8, 1915.

Application filed November 29, 1913. Serial No. 803,810.

To all whom it may concern:

Be it known that I, THOMAS F. GANNON, a citizen of the United States, residing at Rochester, in the county of Monroe and 5 State of New York, have invented new and useful Improvements in Excavating and Filling Apparatus, of which the following is a specification.

This invention relates to apparatus adapted to be used for excavating and filling trenches and the like and it consists in the 10 novel features hereinafter described and claimed.

An object of the invention is to provide 15 apparatus of the character indicated which is of simple structural arrangement and which may be easily and quickly operated or manipulated for the purposes intended. With this object in view the apparatus includes tracks movably mounted upon standards and connected with a shed or structure 20 in which may be located an operating engine. A car is mounted for movement along the tracks and means for operating the car from the engine is provided. A vertically 25 disposed movable beam is mounted upon the car and means is provided for raising and lowering the same. An earth receiving bucket is carried at the lower end of the 30 beam and means is provided for opening and closing the said bucket.

In the accompanying drawing:—Figure 1 is a side elevation of the apparatus. Fig. 2 is an end elevation of the same. Fig. 3 is a 35 detailed elevation of parts of the apparatus with parts in section.

The apparatus comprises tracks 1 which are preferably in the form of channel iron and the said tracks are mounted upon vertically disposed standards 2. The said 40 standards are mounted upon wheels 3. A house or shed 4 is connected to the tracks 1 at one end thereof and is adapted to receive the operating engine 5 of the apparatus.

45 Wheels 6 of a car 7 are arranged to move along the tracks 1 and the said car is provided with hangers 8 carrying rollers 9 which are adapted to move between the upper and lower flanges of the tracks 1. These 50 rollers 9 prevent the car from tilting when subjected to weight at either end thereof and also serve as means to properly maintain the wheels 6 in position upon the tracks. Pulleys 10 are journaled at the upper portion 55 of the car 7 and a cable 11 is trained

over the said pulley and thence around a pulley 12 journaled at that end of the tracks which is remote from the end thereof attached to the house 4 and from the said pulley 12 the cable 11 extends to the car 7 and 60 is attached to the end thereof adjacent the pulley 12. The other end of the cable 11 is operatively connected with the engine 5 in any suitable manner. A cable 13 is connected with that end of the car 7 which is adjacent the house 4 and the other end of the cable 13 is operatively connected with the engine 5. By this arrangement it will be seen that when a pull is exerted upon the cable 13 and at the same time the cable 11 65 is permitted to become slack the car 7 is drawn toward the house 4. On the other hand when the cable 13 is permitted to become slack and a pull is exerted upon the cable 11 the car 7 is moved along the track 70 rails 1 away from the house 4.

A beam 14 is vertically disposed and mounted for movement in a vertical path upon the car 7 and the said beam carries at its lower end a bucket 15 preferably of the 75 clam shell or orange peel type. Cages 16 are mounted upon the car 7 and in the said cages signal men or operatives may stand during the operation of the apparatus. A lever 17 is fulcrumed upon the car 7 and 80 carries at one end a roller 18 which bears 85 against the side of the beam 14. The car 7 is provided at the opposite side of the beam 14 from the roller 18 with a guide 19 and consequently the lever 17 may be moved or 90 swung to such an extent as to cause the roller 18 to clamp the beam 14 against the guide 19 whereby the said beam may be held 95 against vertical movement. A cable 20 is connected at one end with the engine 5 in any suitable manner and is trained over pulleys 21 and 22 journaled upon the frame 7 and is also connected with the lower portion 100 of the beam 14. It is obvious that by drawing upon the cable 20 the beam 14 will be raised and by permitting the said cable 20 to become slack said beam 14 will lower by gravity.

A cable 23 is operatively connected at one 105 end with the blades of the bucket 15 and is trained over pulleys 24 and 25 journaled upon the car 7 and operatively connected with the engine 5. This cable 23 may be used for closing the blades of the bucket 110 when the beam 14 is lowered and at this time

the lever 17 may be operated so as to cause the roller 18 to frictionally bear against the side of the said beam to hold the same in a lowered position while the blades of the 5 bucket are scooping up the earth. A releasing cable 26 (see Fig. 1) is connected with the bucket 15.

A spring pressed pawl 27 is pivotally mounted upon the car 7 and is engageable 10 with the beam 14 or teeth provided thereon for the purpose of holding the said beam positively in an elevated position. When it is desired that the said beam should be lowered the said pawl 27 is swung so that it 15 disengages the beam and consequently the same is rendered free to descend by gravity. Therefore it will be seen that an excavating and filling apparatus of simple structural arrangement is provided and that the parts 20 of the apparatus may be easily and quickly manipulated to remove earth from a ditch or trench and to replace the earth in the same. Furthermore the earth that is elevated from the trench or ditch may be permitted to deposit from the bucket into the body of a 25 wagon or other receptacle provided for its reception.

If desired the beam 14 may be permitted to fall by gravity without the use of a cable

and may be raised by a rack and pinion op- 30 erated by an electric motor or its equivalent.

Having described the invention what is claimed is:—

An apparatus of the character indicated comprising wheel mounted track rails, an 35 engine fixed with relation to the track rails, a wheel supported car mounted upon the track rails, a vertically disposed beam mov- 40 ably mounted upon the car, means for elevat- ing the beam from the engine, a bucket carried at the lower end of the beam, means operated by the engine for closing the bucket, a spring pressed pawl pivotally mounted upon the car and engageable with the beam to positively hold the same in an elevated 45 position, a lever operated friction means mounted upon the car and engageable with the beam to frictionally hold the same in an elevated position, cages carried by the car, the said means for holding the beams in an elevated position being adapted to be operated by operatives occupying the cages. 50

In testimony whereof I affix my signature in presence of two witnesses.

THOMAS F. GANNON.
